CLAIM

The ornamental design for a body for a sled-like sports vehicle, as shown and described.

DESCRIPTION

FIG. 1 is a top perspective view of a body for a sled-like sports vehicle showing our new design;

FIG. 2 is a side elevational view thereof with the opposite side being a mirror image thereof;

FIG. 3 is a bottom plan view thereof;

FIG. 4 is a front elevational view thereof; and

FIG. 5 is a rear elevational view thereof.

The broken lines in the drawing are for illustrative purposes only.
